No. 14,230.

Aug. 21. 1883.

UNITED STATES PATENT OFFICE.

GEORGE J. SHULTS, OF AVOCA, NEW YORK, ASSIGNOR TO SHULTS & BUCK,
OF SAME PLACE.

DESIGN FOR A ROCKING-CHAIR.

SPECIFICATION forming part of Design No. 14,230, dated August 21, 1883.

Application filed May 31, 1883. Term of patent 14 years.

To all whom it may concern:

Be it known that I, GEORGE J. SHULTS, of Avoca, in the county of Steuben and State of New York, have invented a new Design for a 5 Rocking-Chair, of which the following is a full, clear, and exact description.

Reference is to be had to the accompanying photograph, forming part of this specification, in which the figure is a view in perspective of 10 a rocking-chair showing my design.

The invention consists in an ornamental configuration of the front uprights of the rocker, made straight and round for their lower half or portion, and spread out laterally for their 15 upper half or remaining portion by a graceful outward crook or bend immediately above the seat, whereby the chair, apart from any working advantages it may have, and without having resort to a seat wider in front than in its 20 rear, presents an appearance of increased capacity and greater elegance, devoid of that stiffness and sameness which attach to rockers having no such crook or bend in their front uprights, thus making the chair more attractive. 25

A is the splint seat of the "rocker," B its back, CC the front uprights, and DD the arms. The seat A, which may be secured to the back "round," a, side rounds, b b, and front round 30 or portion of the frame, c, in the usual manner, is elevated at its connection with the back round, a, above the side rounds, b b, and is of a gentle or easy curve or slope, as shown at d, from its back to its sides—that is, from the

elevated back round, a, down to the lower side 35 rounds, b b, and intermediate portion between the sides—to impart to the seat a graceful configuration, and to preserve the necessary slant between it and the back free from any awkward bend of the back. The lower half or 40 portion of each front upright, C, is straight and round, as shown at e, and may be of any desired ornamental configuration on its surface; but the remaining or upper halves or portions of said uprights C C are spread out laterally 45 by a graceful outward crook or bend in each immediately above the seat, as shown at f, as and with the advantages as regards effect produced hereinbefore specified.

Having thus fully described my invention, I 50 claim as new and desire to secure by Letters Patent—

The design for a rocking-chair, consisting in the front uprights, C C, made straight and round for their lower halves or portions beneath the seat, and with their remaining or upper halves or portions spread out laterally by an outward crook or bend, f, in each immediately above the seat, the upper half of each standard being arranged in a parallel 55 perpendicular plane with the lower half thereof, said plane being intersected by a horizontal plane passing through the front edge of the seat, essentially as shown and described.

GEORGE J. SHULTS.
